UNITED STATES PATENT OFFICE.

JOHN B. CORNWALL, OF MOLINE, ILLINOIS, ASSIGNOR TO THE BARNARD & LEAS MANUFACTURING COMPANY, OF SAME PLACE.

COCKLE-SCREEN.

SPECIFICATION forming part of Letters Patent No. 276,523, dated April 24, 1883.

Application filed December 11, 1882. (No model.)

To all whom it may concern:

Be it known that I, JOHN B. CORNWALL, of Moline, in the county of Rock Island and State of Illinois, have invented certain new and useful Improvements in Cockle-Screens; and I do hereby declare that the following is a full, clear, and exact description thereof, reference being had to the accompanying drawings, and to the letters of reference marked thereon, which form part of this specification, in which—

Figure 1 is a perspective view of one end of the machine, the belts C being removed. Fig. 2 is a perspective view of the opposite end of the machine. Fig. 3 is a vertical cross-section through the machine, the discharge-hopper being removed. Fig. 4 is an end elevation. Fig. 5 is a side elevation of my invention. Fig. 6 is a detail, showing one of the oblique blades 20 of the drum inside of the cockle-screen B.

Similar letters of reference indicate corresponding parts in the several figures.

My invention relates to certain novel improvements on the cockle-screen for which Letters Patent were granted to me bearing date on the 14th day of September, 1880, and numbered 232,242; and the nature of my invention consists in such combination of parts as will be hereinafter claimed.

A designates the frame of the machine, in which is supported a cylindrical cockle-screen, B, that is embraced about two-thirds of its circumference by means of endless belts C C, preferably made of "two-ply" rubber belting—say about twelve inches wide. These belts C pass around pulleys a, which are endwise adjustable on their shafts, and which are secured thereon by means of set-screws s, as shown in Fig. 5.

The pulley-shaft D is mounted in journal-boxes on top of the frame A, on one side of the vertical plane intersecting the longitudinal axis of the said screening-cylinder B.

The pulley-shaft D' is mounted in journal-boxes on cheek-plates A', and this roller is arranged on the right-hand side of the vertical plane intersecting the longitudinal axis of the screening-cylinder B, beneath said cylinder.

The pulley-shaft D² is arranged on the outside 50 of the frame A, and this shaft has its end bear-

ings in spring-hangers E, which are adjustable by means of screw-bolts p, or their equivalents, for the purpose of regulating the tension or pressure of the belts C C against the circumference of the screening-cylinder. The shaft D² is provided with the pulleys a, held by set-screws, as shown in Fig. 5, which are independently endwise adjustable for the purpose of properly adapting the belts to the circumference of the cylinder B, thereby enabling me to perfectly control and guide the said belts and cause them to run straight, which cannot be done where a single broad apron is employed, as described in my Letters Patent above referred to.

F designates a revolving agitating-wheel, which is arranged inside of the screening-cylinder B, eccentric to the longitudinal axis thereof. The blades b of this wheel F are set obliquely to its axis, or are given a spiral twist, as shown in Fig. 3, so that they operate as conveyers to move the grain through the cylinder, as well as to beat back the grain over the internal surface of this cylinder B, thus causing the cockle to settle in the perforations 75 therein. It will thus be observed that I construct the screening-cylinder B with imperforated portions or blanks (about two to three inches wide, more or less) extending around the cylinder, and lettered c; also a portion, c, imperforated at each end of the cylinder. The object of these imperforated portions c is for the endless belts C to lap on, and they should be wide enough to allow a little sidewise movement of said belts without leaking grain or 80 seeds.

G designates a stationary brush, which is adjustably secured to the cheek-plates A' of the frame A by means of set-screws a^x, and arranged so that it can be made to bear against the inner side of the cylinder B with more or less pressure, as may be required. The object of the brush G is to brush out any wheat which may be lodged in the perforations of the cylinder B, and also to push the cockle through 95 the perforations after the cockle passes above and beyond the shaft D.

A pulley, d, is keyed on one end of the shaft of the agitating-wheel F, to receive motion from a driving-power by means of a belt. (Not shown 100

in the drawings.) A pulley and belt applied to the opposite end of the said wheel-shaft give motion to the shaft D on top of the main frame A. This shaft D gives motion to the 5 belts which partly encircle the screening-cylinder B, and thus the latter is revolved.

In the operation of the machine the cockle lodges in the perforations of the cylinder B, and for a time is prevented from falling through 10 these perforations by the belts C. It is carried up by the revolution of the cylinder until the belts leave the latter to pass over the shaft D, when the cockle drops through the cylinder onto the belts and is carried over the shaft D 15 and discharged. The wheat is fed into the screening-cylinder through a hopper, J, and discharged from the opposite end of the cylinder.

The belts or aprons C are preferably arranged 20 between arc-shaped guide-plates, which are secured to the main frame of the machine.

Having described my invention, what I claim 25 as new, and desire to secure by Letters Patent, is—

1. In a cockle-separating machine, the screening-cylinder constructed with imperforated 30 bands or rings, in combination with supporting and driving belts, substantially in the manner and for the purposes described.

2. In a cockle-separating machine, the combination of a rotary screening-cylinder having 35 imperforated annular portions between the perforated portions, in combination with endless belts, which lap over said imperforated portions and embrace about two-thirds the circumference of said cylinder, substantially as and for the purposes described.

3. In a cockle-separator, the combination of the rotary screening-cylinder, supporting and driving belts, and the endwise-adjustable pulleys therefor, adapted to operate substantially 40 in the manner and for the purposes described.

4. The combination of the rotary screening-cylinder, supporting and driving belts therefor, and adjustable hangers for regulating the tension of the said belts, substantially in the 45 manner and for the purposes described.

5. The combination of the screening-cylinder, the supporting and driving belts therefor, a device for regulating the tension of the belts, and pulleys which are adjustable endwise, all 50 adapted to operate substantially in the manner and for the purposes described.

6. In a cockle-screen, the combination of the screening-cylinder, the supporting and driving belts therefor, and an adjustable brush arranged inside of said cylinder, substantially in 55 the manner and for the purposes described.

7. In combination with the screening-cylinder, supporting and driving belts therefor, an agitating-wheel arranged eccentrically therein, 60 and having blades which are set obliquely to the axis of this wheel, adapted to operate substantially in the manner and for the purposes described.

In testimony that I claim the foregoing as 65 my own I affix my signature in presence of two witnesses.

JOHN B. CORNWALL.
